UNITED STATES PATENT OFFICE.

EDGAR L. WORK, OF COLUMBUS, OHIO, ASSIGNOR OF ONE-THIRD TO F. J. WILLIAMS
AND ONE-THIRD TO FRED ARMSTRONG, OF COLUMBUS, OHIO.

FACE-SHIELD.

1,205,308.

Specification of Letters Patent. Patented Nov. 21, 1916.

Application filed October 23, 1915. Serial No. 57,479.

To all whom it may concern:

Be it known that I, EDGAR L. WORK, a citizen of the United States, residing at Columbus, in the county of Franklin and 5 State of Ohio, have invented new and useful Improvements in Face-Shields, of which the following is a specification.

This invention relates to certain novel and useful improvements in face shields 10 and has particular application to a device of the class described for use by electric welders and others having analogous occupations.

In carrying out the present invention it 15 is my purpose to provide a device of the class described whereby the face and eyes of welders may be protected against flame, sparks, and metal fragments.

It is also my purpose to provide a device 20 of the type set forth wherein the transparent plates employed to protect the eyes may be changed quickly and conveniently and any number of plates of various colors associated together to minimize the effect 25 of the light on the eyes.

Another object of the invention is the provision of a face shield and eye protector which may be supported upon the head of the wearer, which will be strong, compact 30 and light in construction, and which may be worn with ease and convenience and without hindering the movements of the welder.

With the above and other objects in view, the invention consists in the construction, 35 combination and arrangement of parts hereinafter set forth in and falling within the scope of the claims.

In the accompanying drawings, Figure 1 is a view in front elevation of a face shield 40 and protector constructed in accordance with my present invention. Fig. 2 is a view in side elevation of the same. Fig. 3 is a vertical sectional view through the device in use. Fig. 4 is a horizontal sectional view 45 through the device. Fig. 5 is a fragmentary elevation showing the inside of the face shield, parts being shown in section. Fig. 6 is an enlarged fragmentary vertical sectional view through the plate carrier and 50 associated parts. Fig. 7 is a perspective view showing a detail of the invention. Fig. 8 is a fragmentary horizontal sectional view showing another detail of the invention. Fig. 8^a is a broken perspective view 55 of the plate carrier. Fig. 9 is a horizontal

sectional view through the plate carrier. Fig. 10 is a cross sectional view therethrough. Fig. 11 is a perspective view showing a modified form of plate carrier.

Referring now to the drawings in detail 1 60 designates a shield constructed of asbestos or any other suitable material and semi-circular in outline to inclose the face of the wearer. Secured to the lower edge of the shield 1 and depending therefrom is an 65 apron 2 designed to cover the chest of the wearer and operating with the shield 1 to prevent the admission of light, sparks, etc., behind the shield. In the present instance the connection between the shield and the 70 apron embodies pins 3 secured to the shield adjacent to the lower edge thereof and projecting outwardly therefrom and eyelets 4 carried by the apron 2 are designed to receive the pins 3 respectively to hold the 75 apron to the shield. Secured to the inner surface of the shield 1 adjacent to one end thereof is one end of a metal strip 5 while fastened to the inner surface of the shield adjacent to the other end thereof is one end 80 of a metal strip 6. The remaining ends of these strips 5 and 6 overlap each other and formed on the overlapping end of the strip 5 is a collar 7 surrounding the strip 6 while secured to the overlapping end of the strip 85 6 is a headed pin 8 capable of interchangeable engagement with keyhole slots 9 formed in the adjacent portion of the strip 5 and spaced apart along such strip.

10 designates a supporting band having 90 one end secured to the inner surface of the shield 1 adjacent to the upper edge thereof at a point approximately centrally of the length of the shield and secured to the supporting band 10 adjacent to the remaining 95 end thereof is a strap 11 having the central portion spaced apart from the supporting band and passed through the space between the strap and the supporting band are the overlapping portions of the strips 5 and 6. 100

Formed in the shield 1 approximately centrally thereof is a sight opening 12 and secured to the inner surface of the shield contiguous to the lower wall of the side opening is a plate 13 having the inner edge 105 formed centrally with a depression 14 to accommodate the nose of the wearer, and curved at opposite sides of the depression as at 15 to conform to the curvature of the face at the sides of the nose secured to the 110

inner surface of the shield adjacent to the respective end of the opening 12 and projecting into the shield are flaps 16 adapted to engage the opposite sides of the head of the wearer at the temple. A head piece 17 is also fastened to the inner surface of the shield at the upper side of the sight opening 12 and this head piece is designed to bear against the forehead of the wearer, while disposed below the sight opening adjacent to the lower edge of the shield is a chin rest 18 and the head piece and chin rest are preferably covered with suitable pads respectively designed to bear against the chin and the forehead of the wearer. Secured to the outer surface of the shield 1 and projecting downwardly therefrom is a short hood 19 surrounding the sight opening 12 and corresponding to the shape of such opening and secured within the hood 19 at the inner end thereof is a frame 20 having the outer edge of the top and bottom and end bars formed with communicating grooves within which are disposed padding strips 21. The lower wall of the hood 19 is formed with cut out portions 22 spaced apart and depending from the lower bar of the frame 20 are lugs 23 projecting through the respective cut out portions 22. These lugs 23 are equipped with pivot pins 24 alining axially with each other. 25 designates a holder comprising top and bottom bars 26—26 and an end bar 27 interconnecting the top and bottom bars at one end of the holder and the inner edge of the respective bars 26 and 27 are formed with communicating grooves 28. At the open end of the holder the top and bottom bars are connected together by means of strips 29 spaced apart in parallelism and each having the extremities thereof formed integral with the top and bottom bars at one side of the holder. Formed on the bottom bar of the holder 25 are lugs 30 corresponding to the lugs 23 and pivoted upon the pins 24 respectively. This holder 25 is capable of swinging movement into and out of the hood 19. In order to hold the holder in actuated position any suitable means may be employed. In the present instance a retractile spring 31 has one end secured to the outer surface of the shield adjacent to the bottom wall of the hood and the remaining end fastened to a pin 32 carried by the end bar 27 of the holder and as the holder is swung from one position to the other, the spring 31 passes the axes of the pivot ends and exerts its influence to hold the holder 25 against accidental movement. 33 designates a plate carrier which, in the present instance is identical in construction to the holder 25 and is adapted to slide into and out of the holder by way of the open end thereof and disposed within the carrier 33 are transparent plates 34 differ-

ently colored. Also slidable into and out of the holder and adapted to lie in face to face contact with the outermost plate is a foraminous protecting plate 35 composed of metal or the like. A spring gage 36 of suitable construction, is secured to one of the bars 26 of the holder at the open end of such holder and engages the adjacent end of the plate carrier, when the latter is inserted in the holder to prevent the accidental withdrawal of the plate carrier from the holder. 70 75

In the present instance a transparent plate 37 preferably amber colored is disposed within the sight opening 12 and the marginal edges thereof rest against the rear edge 80 of the bars forming the frame 20, while engaging the inner surface of the plate 37 at the opposite ends thereof are spring fingers 38 secured to the upper surface of the plate 13 at the ends thereof, the fingers 38 acting 85 to hold the plate 37 in proper position in the sight opening.

Spanning the plates between the flaps 16 and resting upon the upper edges of the latter adjacent to the inner surface of the shield 1 is a strip 39 having the ends thereof projecting beyond the flap and turned down as at 40. This strip 39 is arranged below the head piece 17 and formed with a series of openings 41 through which air may pass 95 into the space between the flaps and the nose plate for ventilating purposes.

In the use of the device; the shield 1 is placed about the face while the strips 5 and 6 encircle the head and the supporting band 10 rests upon the top portion of the head, thereby holding the shield in position. When the shield is over the face of the wearer the front and sides of the face are covered and the apron 2 covers the chest. 105 The head piece 17 and the chin rest 18 engage the forehead and chin respectively to hold the front portion of the shield spaced apart from the face, while the nose plate 13 and flaps 16 protect the eyes from any 110 sparks or metal fragments which may pass beneath the shield. After the shield has been adjusted upon the head, the desired combination of plates is inserted in the carrier 33 and the latter placed in the holder 115 25 and the holder swung into the hood 19. The eyes of the wearer are thus protected from the intensity of the welding flame.

If desired the holder 25 may be constructed from a piece of foraminous metal 120 as shown in Fig. 11 and when thus formed the protecting plate is an integral part of the carrier.

It will be noted that the plates 34 may be slipped into and out of the carrier by way 125 of the open end thereof and may be used either single or in combination with one another according as it is desired to control the effect of the light on the eyes.

The protecting plate in front of the dif- 130

ferently colored transparent plates 24, is preferably although not necessarily formed of brass or material having analogous properties, as the brass will throw off any metal fragments which may strike the same.

While I have herein shown and described certain preferable forms of my invention, by way of illustration I wish it to be understood that I do not limit or confine myself to the precise details of construction herein described and delineated as modifications and variations may be made within the scope of the claims and without departing from the spirit of the invention.

15 I claim:—

1. An eye guard for electric welders and the like comprising a plate carrier embodying longitudinal guards and an end bar having the inner edge thereof formed with 20 grooves, the remaining end of said carrier being open, and plates slidable into and out of said carrier by way of the open end thereof and having the marginal edges thereof engaged in the grooves in said longitudinal 25 bars and said end bars.

2. A face shield and eye protector for electric welders comprising a semi-circular shield adapted to inclose the face of the wearer, means for supporting said shield 30 upon the head of the wearer, said shield having an opening formed therein in line with the eyes and a plate holder movable into and out of said opening and transparent plates of different colors interchangeably associated with said holder.

3. A face shield and eye protector for electric welders comprising a semi-circular shield adapted to inclose the face of the wearer, said shield having an opening 40 formed therein in line with the eyes, a plate holder movable into and out of said opening, transparent plates of different colors interchangeably associated with said holder and means for maintaining said holder in 45 position in said opening.

4. A face shield and eye protector for electric welders comprising a semi-circular shield adapted to inclose the face of the

wearer, means for supporting said shield upon the head of the wearer, said shield 50 having an opening formed therein in line with the eyes, a plate holder movable into and out of said opening, transparent plates of different colors interchangeably associated with said holder, a hood secured to the 55 outer surface of said shield and surrounding the opening therein and designed to embrace the edges of said holder.

5. A face shield and eye protector for electric welders comprising a semi-circular shield adapted to inclose the face of the wearer, means for supporting said shield upon the head of the wearer, said shield having an opening formed therein in line with the eyes, a plate holder movable into and out 60 of said opening, transparent plates of different colors interchangeably associated with said holder, an apron detachably connected to the lower edge of said shield, a head piece adapted to engage the forehead 65 of the wearer and a chin rest on the inner surface of said shield adapted to engage the chin of the wearer and coöperating with said head piece to hold the shield spaced apart from the face. 75

6. A face shield and eye protector for electric welders comprising a semi-circular shield adapted to inclose the face of the wearer, means for supporting said shield upon the head of the wearer, said shield having an opening formed therein in line with the eyes, a plate holder movable into and out of said opening, transparent plates of different colors interchangeably associated with said holder, flaps on the inner surface 80 of said shield at opposite sides of the opening therein adapted to engage the head of the wearer at the temples and a nose plate on the inner surface of said shield below the opening therein. 90

In testimony whereof I affix my signature in presence of two witnesses.
